UNITED STATES PATENT OFFICE

CHRISTIAN BALDENHOFER, OF SPRINGFIELD, OHIO

PACKAGING MACHINE

Application filed April 26, 1928. Serial No. 273,105.

My invention relates to packaging machines.

It is the object of my invention to provide means for packaging material that comes in 5 strands or filaments, such as steel wool, textile materials and food products that are formed in attenuated filaments.

Referring to the drawings:

Figure 1 is a side elevation from the operator's side of the machine;

Figure 2 is a rear elevation of the machine;

Figure 3 is a perspective of the machine from the front thereof;

Figure 4 is an end elevation on the left hand 15 side of the machine;

Figure 5 is an end elevation on the right hand side of the machine;

Figure 6 is a diagrammatic view of the position of the several parts as a filled carton is 20 about to be removed from the machine;

Figure 7 is a similar view with the filled carton removed from the machine and a new charge of material being accumulated on the loading spindle;

Figure 8 is a similar view showing the load 25 on the spindle accumulated and the new carton being opened for the reception of the load;

Figure 9 is a similar view showing the load 30 being inserted in the new carton;

Figure 10 is a top plan view of the carton handling mechanism showing the parts in the position corresponding to those in Figure 8 with the carton being opened;

Figure 11 is a similar view with the opening mechanism in withdrawn position, as in 35 Figure 9, with the holders for the carton still in position but the opening mechanism withdrawn so that the carton can be loaded, as in

Figure 9;

Figure 12 is a similar view showing the parts in position with the holders withdrawn so as to permit of the removal of the loaded carton as in Figures 6 and 7;

Figure 13 is a detailed view of the holder cam which actuates the holder into holding position and holds it there through opening and loading of the carton;

Figure 14 is a section on the line 14—14 of 50 Figure 10 showing the parts in the position

shown in Figure 8 where the carton is being opened.

Figure 15 is a similar view showing the carton just being opened.

Figure 16 is a top plan view of the holding 55 fingers where the cartons are located.

Figure 17 is a detail view partially in section showing the arrangement of the carton elevating mechanism and the carton opening and discharging mechanism;

Figure 18 is a bottom plan view of the cut off mechanism for cutting the filaments or strands in predetermined lengths;

Figure 19 is a view of the same mechanism on the lines 19—19 of Figure 18;

Figure 20 is a side elevation partially in section in detail of the filament trap door feed

Figure 21 is a diagrammatic view of the loading spindle in its retracted inoperative 70 position;

Figure 22 is a similar view in operative position;

Figure 23 is a section through the spindle head and the actuator head

Figure 24 is a vertical section through the supporting and driving sleeve of the loading spindle;

Figure 25 is a section on the line 25—25 of Figure 24;

Figure 26 is a detail fragmentary view of the operative mechanism for reversing the direction of movement of the loading spindle and of the cam for retreating the loading spindle and advancing it showing the parts in 85 the retracted reverse movement position;

Figure 27 is a similar view showing the parts in advanced forward movement or winding position;

Figure 28 is a section on the line 28—28 of 90 Figure 2;

Figure 29 is a section on the line 29—29 of Figure 27 looking in the direction of the arrows

Figure 30 is a section on the line 30—30 of 95 Figure 27 looking in the direction of the arrows.

The machine of my invention is fed with a plurality of continuous strands of material to be loaded, such as steel wool.

After the strands have been fed through the machine a predetermined length down to the trap door of the feeding chute, I cut off the strands in predetermined lengths, in the meanwhile opening the trap door and allowing the strands to be fed to the winding spindle. These strands of predetermined length are wound on the spindle which is traveling in a winding direction. A carton is then 10 opened up and held in open position while the loaded spindle is advanced with its load into the interior of the carton. Then the spindle is reversed in its direction so that it may be removed from the interior of its load 15 leaving the load in the carton and, upon being retreated to its initial position, it comes to rest until the winding operation has to start again.

Then the loaded carton is elevated and 20 moved from the machine. A new carton is moved into position ready for being opened from its folded position to its open position to receive its load.

In detail, referring to the drawings, my 25 machine consists of the following parts: The legs 1 support a table consisting of the side plates 2 and 3 on the front and back respectively of the machine. These side plates have mounted upon them a table 4. Mounted 30 upon this table on the right hand end are a pair of tubular, vertical supports 5 and 6 and on the left hand end a single tubular support 7. These three supports are adapted to carry the feed table 8.

35. Feed table

On the feed table 8 is mounted a supporting bracket 9 which carries a pair of horizontal bearing sleeves 10 and 11. These sleeves 40 carry respectively the feed driving shaft 12 and the feed driven shaft 13. On these shafts are mounted pinions 14 and 15 which intermesh so that the two feed shafts turn together.

On each feed shaft there is mounted a feeding head consisting of a disk 16 and a plurality of parallel spaced feeding fingers 17 which extend parallel to the axis of the shaft on which they are mounted. Within the cylindrical space formed by these spaced fingers 50 in the resilient tubular member 18. These fingers are so arranged that they interlock or intermesh as they rotate, one finger on one shaft being arranged to project between the adjacent fingers on the other shaft but not 55 to engage them so that the fibers or strands of wool, or other material, will be engaged frictionally when passing between these feeders and engage frictionally by the resilient filler 18 without injuring the filaments or fibers, but at the same time, properly feeding them as desired.

The shaft 12, which is the driving shaft of the feeding mechanism, is supported on its rear end upon a bracket 19. The shaft carries 65 a sprocket 20 which is actuated by the chain

21. An idler sprocket 22 is carried on an arm 23 on the bracket 19 in order to maintain the chain taut. This chain is, in turn, mounted upon a driving sprocket 24. The driving sprocket 24 is carried on a shaft 25 supported in the bracket 26'. This shaft 25 carries a gear 26" which, in turn, is engaged with an idler gear 27 carried on the shaft 28 which, in turn, is supported by the arm 29 mounted in the bracket 30. This idler gear meshes with the gear 31 that is carried in the bracket 32 and drives the shaft 33. The sprocket 24 and its shaft 25 is driven by means of a sprocket 34 on the shaft 25 which, in turn, is actuated by a chain 35. This chain, in turn is driven by a sprocket 36 which is mounted on the shaft 37. This shaft is carried in depending brackets 38 on the bottom of the table 8. It also carries the driving sprocket 39 that is actuated by the driving chain 40 which extends to the bottom of the machine where the chain is actuated by the driving shaft 41 of the speed reducer 42 that is actuated by the motor 43.

Cut-off mechanism

The shaft 33 has its left hand end supported in a bracket 44 on the table 8. It is provided at its free end with a bevel gear 45 which meshes with another bevel gear 46. The details of this mechanism will be seen in Figures 18 and 19. Figure 19 is viewed from the back of the machine. The gear 46 is loosely mounted upon the cutter shaft 47. The gear is hollow, as at 48, and has an upwardly projecting pin 49 extending into the hollow area within the gear 46. Mounted within this hollow portion 48 of the gear 46 is a cylindrical member 50 having a depending pin 51 adapted to engage with the upstanding pin 49 on the gear 46. The cylindrical member 50 is pinned by the pin 52 to the cutter shaft 47. The upper end of the cylindrical member is provided with an arm 53 that is connected to a helical spring 54, the free end of which is permanently attached to the standard 55 carried on the feed table 8.

The lower end of the shaft 47 projects through a bearing sleeve 56 which is formed as a part of the table 8. It is supported in position by the collar 57 that is keyed thereto which rests upon the bearing sleeve 56. The lower end of this shaft passes through a stationary shearing shoulder 58. The shaft itself projecting below the shearing shoulder 58 carries a horizontally extending swinging knife 59 which is spring pressed in position by the spring 60. As this knife swings with the shaft 47 it serves to cut off the strands which are being fed by the feed mechanism into the hopper or guide chute 61. In order to effect this cutting operation it is necessary that the knife 59 swings suddenly with great force to bring about a clean shearing of the threads or strands, such as steel wool.

For this purpose, the gear 45 turns the

gear 46 and the pin 49 engages the pin 51. This serves to move the shaft 47 with its knife and to rotate it into cutting position in the direction of movement when it is actually cutting the strands. This movement of the knife to cutting position continues against the resistance of the spring 54 until the pin 49 and the pin 51 slip by one another whereupon the spring 54 moves suddenly to its initial position causing it to cut the strands in two which are interposed between it and the shearing shoulder 58 having been fed through the opening 63.

Guide mechanism

15 The chute 61 constitutes a guiding mechanism. A rear wall 61^a and a side wall 61^b form the chute beneath the knife drum 62, within which the knife 59 rotates. The feed table 8 has an opening 63 adjacent the shearing shoulder 58 through which the strands are inserted. This opening is directly above the area designated 61^c which is defined on one side by the guiding plate 64. The opening thus arranged for the direction of the strands is controlled and, upon occasion, closed by the trap door 65 which prevents the wool from dropping down on the wrapping spindle 66 until the spindle is in proper position for carrying out the wrapping operation. The details of this trap door mechanism are seen in Figure 30. The door 65 is mounted upon an actuating shaft 66 carried in spaced brackets 67 upon the table 4 of the machine. 25 The end of the shaft 66 is provided with an arm 68 connected to a pitman 69 which, in turn, is connected to a bell crank 70 mounted on a bracket 71. This bell crank is maintained in a predetermined position by a spring 72 which is connected to the bell crank at one end and to the stationary standard 67 at the other end. The end of the bell crank connected to the spring carries a pitman 73, the free end of which is connected to a cam lever 74 that is pivotally supported at 75 on a bracket 76 carried on the table 4. The cam lever 74 projects through an opening 77 in the table floor and extends to a point where it is engaged by a cam 78 mounted on the shaft 79. This shaft 79 and the method of driving it can be seen clearly in Figure 28. The shaft 79 is driven by the bevel gear 80 which, in turn, meshes with the bevel pinion 81 carried on the shaft 82 on the back of the machine. This shaft 82 carries a sprocket 83 that, in turn, is driven by a chain 84 that extends down to a sprocket 85 on the speed reducer shaft 41 that is driven by the motor 43.

Spindle loading mechanism

60 The spindle loading mechanism is actuated, as to its movement, from inoperative to winding position and from winding to loading position and back to its initial position

by the cam 85 mounted on the shaft 79 and driven thereby. This cam and associated mechanism will be found illustrated in detail in Figures 21, 22, 23, 24, 25, 26, 27 and 28. The cam 85 has a groove 86 in which travels a cam roller 87 on the lever 88 that is pivotally supported on the shaft 89 in the sleeve 90 carried on the inside of the rear wall 3 of the machine. The cam is so arranged that, when the roller gets to the point designated 91 the spindle will be at its most advanced position and as the cam travels to the position designated 92 the spindle will be in its retreated position. But it is arranged to dwell, as at 93, while it is in its forward position and has reversed its direction of movement to unwind itself from the interior of the roll of steel wool which constitutes the load designated 94 to be placed in the carton. Having disengaged itself by reversing the rotation and the withdrawal of the knife edges 66^a on the spindle 66 which causes the wool to wrap around the spindle, the spindle can then be withdrawn to the position shown in Figure 6.

90 The spindle itself carries a sprocket 95 which in turn is driven by a chain 96. This chain passes around a large sprocket 97 carried on a shaft 98 beneath the table 4. The shaft 98 carries, in turn, a small sprocket 99 that is actuated by a chain 100. The chain 100 is driven by the sprocket 101. (See Figure 29.) The sprocket 101 is mounted on the shaft 102. This shaft carries a sprocket 102. The sprocket 103 is driven by the chain 104 through a sprocket 105 that is carried on the stub shaft 82. The stub shaft 82 is mounted in the bearings 107 and 108 on the rear wall 3 of the machine. The sprocket 83 on the shaft 82 is driven by the main bearing chain 84. It will be observed from Figure 28 that the chain 104 is carried on an idler sprocket 106 which in turn is carried on the shaft 109 which is journaled in the bracket 110. The shaft 102 is likewise carried in the journal brackets 111 and 112.

Reversing mechanism for loading spindle

115 The spindle is reversed in direction, winding the wool into a load in one direction and then reversing the spindle movement in order to leave the load within the carton. For this purpose the sprocket 101 is provided with a toothed hub 113 which engages with the toothed side 114 of the slideable clutch 120 member 115 which is engaged in a groove 116 by the yoke 117. The other side of this member 115 is provided with teeth 118 for engaging with corresponding teeth 119 on the hub of the sprocket 120. This sprocket 125 carries the chain 121, the upper side of which engages with the sprocket 122 on the shaft 98 so that the direction of movement of the shaft on the spindle 66 is reversed.

120 The chain 121 is carried on an idler 123

sprocket 123 supported on a bracket 124 on the inside of the side wall 2 of the machine.

The spindle shaft 66 is carried in the sleeve 125 of the supporting bracket 126. This sleeve 125 is a bearing sleeve keyed by the key 127 to the shaft 66. The sprocket 95 is likewise keyed to this shaft so that the shaft can slide through it while the sprocket can turn with it. On the free end of the shaft 66 is a head 128 having a cross member 129 fitting within the jaws 130 on the end of the lever 88. This cross member 129 on either side extends into a slot 210 formed in upright spaced guide members 131 carried on the table 4. The shifting of the clutch member 115 is effected through the yoke 117 which is carried on the lever 132 which is pivoted at 133. The lower end of this lever carries a cam roller 134 that is actuated by the cam 135.

20 The spindle shaft proper 66 has an annular guard 66^b for limiting the position of the load on the spindle.

Box supply mechanism

25 The box supply mechanism is shown in detail in Figures 14, 15, 16 and 17. A supply chute 136 is provided in which the cartons in flat folded condition are located upon an elevator 137. This elevator is connected on either side to chains 138 which pass over guide pulleys 139 and 140. The free end of the chain depends with a counter balancing weight 141 on the end thereof. Mounted on 30 the shaft 163 is a crank 202 connected to a pitman 203 carrying a strap eccentric 204 on its free end surrounding an eccentric 205 that is mounted on the shaft 206. This eccentric shaft 206 carries a sprocket 207 which is engaged by a pawl 208 carried in the frame 209. Thus, the elevator is moved by the eccentric step by step in synchronism with each cycle of operation to present a new folded box to be opened by the opener 152.

45 There is a chain on either side of the elevator. The top of the elevator is provided with spring hinge plates 142 held in horizontal position by the springs 143 so that the spring plates overlap the edges of the folded 50 cartons which have the side walls 144, 145, 146 and 147. These spring plates overlap the corners 148 and 149 of the boxes. The other corners are designated 150 and 151. The function of these plates is to hold the 55 corners of the boxes yieldingly while the other corners are being engaged interiorly by the box spreader 152 which is introduced into the interior of the box for opening the box.

Box opening mechanism

This box opening mechanism consists of a triangular shaped spreader 152 that is carried on the shaft 153. This shaft has a cross member 154 mounted in a yoke 155 of the

lever 156. The cross member travels in slots 157 of parallel spaced guide members 158 on the table 4. The lever 156 is pivoted near its lower end at 159. Its lower end carries a cam roller 160 which travels in the slot 161 of the cam 162 on the shaft 163. This shaft 163 extends between the side walls of the machine and through them and is driven by the sprocket 164 which, in turn, is actuated by the chain 165, this chain receiving its power from the sprocket 166 on the shaft 79.

70 The reciprocation of the opener 152 serves to open the box. In order to hold this box in its open position and to form limiting members to keep the box from being pulled out of the machine when the opener is thrust on the interior thereof I provide reciprocating holding jaws which are moved into position to hold the box while it is being opened and while it is being loaded but which are withdrawn at the proper interval after the box is loaded and when the box is being ejected from the machine.

75 In order to show the successive stages of operation of this box holding mechanism and box opening mechanism, I have provided the views shown in Figures 10, 11, 12, 13, 14, 15, 16 and 17.

80 I provide a pair of spaced slotted guide members 167 and 168 which are bolted by the bolts 169 to the supporting blocks 170 mounted on the table top 4. On either one of these blocks 170 are laterally extending brackets 171, the free ends of which act as supports for the helical springs 172 which are connected at their inner ends to eyes 173 that are attached to the sliding plates 174, the inner ends of which are formed into angular box supports for engaging the upper walls 144 and 145 of the box when it is in its expanded condition. These box supports are designated 175. Behind each of the box supports 175 are located the rollers 176 on the vertical shafts 177 mounted on the slides 174.

85 On either side of the box there are located holder cams consisting of flat plates having fingers 178, cam surfaces 179, and body members 180, such body members 180 having slots 181 through which project bolts 182 carried by the spaced cam actuating arms 183. These cam actuating arms 183 are connected together by the plates 184. These inner ends of the cam actuating arms so connected are adapted to move with the cross member 154 and to reciprocate in the guides 167 and 168.

90 The side members 185 carry spring pressed plungers 186 on their forward ends, which are adapted to yieldingly engage the ends 187 of the holder cams 178, 179. These yielding pins 186 serve to press the holder cams into position to move the box holders 175 into inner position.

Box ejecting mechanism

95 The box ejecting mechanism consists of a

pitman 188 pivoted on a cross member 189 which works in a slot 157. A spring 190 is connected to the sliding members 184 at 191 and to a pin 192 at the point of pivotal mounting of the pitman 188. The free end of the pitman is formed into a jaw 193 that is pivoted at 194 to the lower end of the elevating lever 195. This elevating lever is pivoted at 196 to a bracket 197. The lever carries a cam arm and a box engaging finger. The box engaging finger is designated 198 and is adapted to extend inside of the box to lift it when the box holders have been withdrawn laterally by the springs 172. That portion of the cam arm designated 199 is adapted to rest upon a guide roller 200 carried on the spindle 201 on the upright 7; when the cam levers so rest on the roller it is in horizontal position for engaging with the box. When the cam lever 200 is in engagement with the roller it is going into the box and when the roller engages with the spindle 201 the box up-
engages with the spindle 201 the box is being elevated in filled condition.

25 *Method of operation*

Assuming that the box has been filled, as in Figure 6, the box lifting finger 198 will be inserted into the box on the interior thereof on the inside of the corner 150. At that time the box holders are withdrawn and the box is filled. This filled box has the lifting finger inserted in it and as the lever 195 has its upper end moving forwardly the several portions of the cam lever pass over the roller 200 bringing about an elevation of the box where it may be lifted off by the operator and the ends of the box closed. While this is going on strands of wool have been fed by the feeding mechanism through the opening 63 into the path of the knife 59. When a suitable length of wool has been fed through the knife 59 is released under the tension of the spring 74 and suddenly swings across the wool cutting it in two. Its tendency to drop down at its lower end in the path of the revolving spindle 66 is restrained by the trap door 65 which does not open until the spindle has been moved to a position beneath the trap door and is revolved in a winding direction. The strands are then wound on the spindle, as shown in Figure 7, until the entire length of strands has been completely wrapped on the spindle forming the bundle or load 94. While this has been going on the lever 156 has been advanced by the cam 162 carrying with it the box opener 152 which has been inserted within the next folded box. This forward movement is also adapted to 50 press the holder cams forwardly moving the box holders 175 towards each other. The continued movement of the parts withdraws the box opener but leaves the cams 179 in position to hold the box holders in their inner position because the cam actuating arms 183 can move

relatively to the holder cams because of the bolt 182 working in the slot 181. As soon as the box opener 152 has been withdrawn the load of wool has been completely wound and it is thrust into the open box, as in Figure 9 by reason of the movement of the lever 88 under the influence of the cam 85. During this time the spindle 66 is rotating in a winding direction. As soon as it gets within the box the cam 135 gets to a point where it shifts the clutch 115 reversing the direction of the spindle 66 and simultaneously the cam groove 86 working on the roller 87 of the lever 88 starts to withdraw the spindle 66 leaving the load 94 in the box. When the spindle reaches its rearmost position the clutch is again shifted and the spindle starts to revolve in its forward direction again, whereupon the rewinding operation takes place as soon as the trap door permits the wool to have access to the revolving spindle.

By the time that the load has been deposited in the box the lever 156 is withdrawn to a point where the bolts 182 get to the end of the slots 181 and withdraw the holder cams allowing the box holders to separate under the influence of their springs so that the box ed in the box the lever 156 is withdrawn to a ejecting finger 198 with its cam arm may be inserted within the box and start to elevate the box as it is pushed backwardly due to the engagement of the jaw 155 with the cross spindle or guide 189 of the pitman 188 which is attached to the lower end of the lever 195.

It will be understood that I desire to comprehend within my invention such modifications as may be necessary to adapt it to varying conditions and uses.

Having thus fully described my invention, what I claim as new and desire to secure by Letters Patent is:

1. In a packaging machine for strand material, means to feed the strands, means to sever the strands in predetermined lengths, means to guide the strands to a winding means to wind the strands into a load, means to insert the load in a carton, means to withdraw the winder from the load in the package, means to deliver a carton, and means to open the carton.

2. In a packaging machine for strand material, means to feed the strands, means to sever the strands in predetermined lengths, means to guide the strands to a winding means to wind the strands into a load, means to insert the load in a carton, means to withdraw the winder from the load in the carton, means to deliver a carton, means to open the carton, and means to hold the carton in open position while being loaded.

3. In a packaging machine for strand material, means to feed the strands, means to sever the strands in predetermined lengths, means to guide the strands to a winding means to wind the strands into a load, means

to insert the load in a carton, means to withdraw the winder from the load in the carton, means to deliver a carton, means to open the carton, means to hold the carton in open position while being loaded and means to release the carton after loading.

4. In a packaging machine for strand material, means to feed the strands, means to sever the strands in predetermined lengths,

,10 means to guide the strands to a winding means to wind the strands into a load, means to insert the load in a package, means to withdraw the winder from the load in the carton, means to deliver a carton, means to open the carton, ,15 means to hold the carton in open position while being loaded, means to release the carton after loading, and means to eject the loaded carton.

5. In a packaging machine for strand material, means for continuously feeding strand material, means for cutting said strand material intermittently in predetermined lengths, means for guiding the lengths so cut to a winder, means for preventing the strands ,20 so cut from reaching the winder until the winder is in winding position, means for opening said preventive means, means for winding said strands into a load, means for moving the load in wound condition to a ,25 loaded position within a carton, means for holding a carton in open condition to be loaded, means for reversing the direction of the winder, means for withdrawing the winder, and means for releasing the filled carton.

25 6. In a packaging machine for strand material, means for continuously feeding strand material, means for cutting said strand material intermittently in predetermined lengths, means for guiding the lengths so cut to a ,30 winder, means for preventing the strands so cut from reaching the winder until the winder is in winding position, means for opening said preventive means, means for winding said strands into a load, means for moving ,35 the load in wound condition to a loaded position within a carton, means for holding the carton in open condition to be loaded, means for reversing the direction of the winder, means for withdrawing the winder, and ,40 means for releasing the filled carton, all of said means being driven synchronously from a common source of power.

7. In a method of packaging material in the shape of strands, feeding the strands to ,45 a machine, severing the strands in lengths, winding the strands in a roll, inserting the roll in a carton, delivering the carton for loading, opening the carton for loading, and holding the carton open for loading.

60 8. In a method of packaging material in the shape of strands, feeding the strands to a machine, severing the strands in lengths, winding the strands in a roll, inserting the ,65 roll in a carton, delivering the carton for loading, opening the carton for loading,

holding the carton open for loading, and ejecting the loaded carton from the machine.

9. In a packaging machine for strand material, a loading mechanism comprising spaced synchronously moving loading members having spaced fingers adapted to interlock one with the other in spaced relation, and a resilient means within one of said spaced feeding means.

,70 10. In a packaging machine for strand material, a cutting means comprising means to guide strands past a shearing knife, a shearing knife, a shearing shoulder against which the strands abut when being sheared, means for moving said knife away from the path of the strands as they pass by the shearing shoulder, yielding means adapted to be put under tension when the shearing knife is moved away from the shoulder, and means adapted to move the knife to a predetermined point and then release it, to be suddenly returned by the yielding means to shear the strands.

,75 11. In combination, a supporting table, a shaft vertically disposed therethrough, a shearing shoulder carried by said table, a shearing knife adapted to pass adjacent said shearing shoulder carried on said shaft, a bevel gear loosely mounted on said shaft having a projecting pin, a pin carried on said shaft adapted to engage therewith, yielding means adapted to resist the rotation of said shaft, and a driving gear engaging with the first mentioned gear whereby said shaft is rotated a predetermined distance while the pins are engaged with one another and when the pins are disengaged, the yielding means moving said shearing knife adjacent the shearing shoulder to shear the strands.

,80 12. In a packaging machine for strand material, a winding and loading mechanism comprising a winding spindle, means thereon for engaging with the strands in one direction of rotation with the spindle, and disengaging with the strands in the opposite direction of rotation with the spindle, means to rotate said spindle in one direction, means to reverse the rotation in the other direction, and means to advance and withdraw said spindle while it is being rotated in either direction.

,85 13. In a packaging machine for strand material, a winding and loading mechanism comprising a reciprocating rotating shaft, means to rotate said shaft in either direction, cam control means for reversing the direction of motion at predetermined intervals, cam control means for reciprocating said shaft at predetermined intervals, both of said cam means for rotation and reciprocation being driven from a common source of power, and means to guide said spindle in its rotation and reciprocation.

,90 14. In a packaging machine for strand material, in combination in a loading and wind-

ing mechanism, a splined shaft having a winding head with lateral projections thereon to engage strands in one direction and disengage them in the other direction, means to support and guide said shaft, means to 5 rotate said shaft in opposite directions, clutch means for determining the direction of rotation, cam means for operating said clutch, cam means for controlling the reciprocation of the shaft, and a common power 10 means for furnishing the power for rotation and reciprocation of the shaft.

15. In a packaging machine for strand material, in combination in a loading and winding mechanism, a splined shaft having a winding head with lateral projections thereon to engage strands in one direction and disengage them in the other direction, means to support and guide said shaft, means to rotate 20 said shaft in opposite directions, clutch means for determining the direction of rotation, cam means for operating said clutch, cam means for controlling the reciprocation of the shaft, and a common power means for 25 furnishing the power for rotation and reciprocation of the shaft, said winding head comprising a tapered shaft portion and a shoulder portion, the projections on the tapered portion being near the outer extreme end 30 thereof.

16. In a packaging machine for strand material, a strand guiding mechanism comprising a chute, a trap door pivotally mounted adjacent the bottom of the chute, cam actuated means for operating said door at intervals, 35 a reciprocating winding mechanism located below said door adapted to rotate in opposite directions, cam means for controlling the direction of rotation and reciprocation of the 40 winding means, all of said cam means being operated synchronously from a common source of power whereby when the winding means is below the trap door to receive strands from the guiding means, the door 45 will be opened and the winding operation will take place, but when the winding means is not in winding position the door will be closed.

In testimony whereof, I affix my signature.
50 CHRISTIAN BALDENHOFER.
